US00D562272S

(12) **United States Design Patent** (10) **Patent No.:** **US D562,272 S**
Su et al. (45) **Date of Patent:** **** Feb. 19, 2008**

(54) **LIGHT EMITTING DIODE (LED)**

(75) Inventors: **Wen-Lung Su**, Hukou Township, Hsinchu County (TW); **Hsiang-Cheng Hsieh**, Hukou Township, Hsinchu County (TW)

(73) Assignee: **Lighthouse Technology Co., Ltd.**, Hsinchu County (TW)

(**) Term: **14 Years**

(21) Appl. No.: **29/269,979**

(22) Filed: **Dec. 13, 2006**

(30) **Foreign Application Priority Data**

Nov. 17, 2006 (TW) 95306391

(51) **LOC (8) Cl.** **13-03**

(52) **U.S. Cl.** **D13/180**

(58) **Field of Classification Search** D13/180; D26/2; 257/79, 80, 81, 82, 88, 89, 95, 98, 257/99, 100, 678, 680, 433, 434; 313/483, 313/498, 500; 361/820; 362/555, 800

(57) **CLAIM**

We claim the ornamental design for light emitting diode (LED), as shown and described.

DESCRIPTION

FIG. 1 is a perspective view of a light emitting diode (LED) showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a second perspective view of the light emitting diode.
